UNITED STATES PATENT OFFICE.

GEORGE AINSWORTH, OF GREAT NECK, NEW YORK, ASSIGNOR TO BEVERLY LIGHTS CORPORATION, OF PROVIDENCE, RHODE ISLAND, A CORPORATION OF RHODE ISLAND.

DESIGN FOR A WALL PLATE FOR LIGHTING FIXTURES.

Application filed September 22, 1922. Serial No. 3,795. Term of patent 14 years.

To all whom it may concern:

Be it known that I, GEORGE AINSWORTH, a citizen of the United States, and residing at Great Neck, in the county of Nassau and State of New York, have invented a new, original, and ornamental Design for a Wall Plate for Lighting Fixtures, of which the following is a specification, reference being had to the accompanying drawing, forming part thereof.

The figure is a front view of a wall plate for lighting fixtures showing my new design.

I claim—

The ornamental design for a wall plate for lighting fixtures as shown.

GEORGE AINSWORTH.
